MAGNETIC RECORDER OR SIMILAR ARTICLE

Roberto O. Alvarado, Miraflores, Peru

Application February 11, 1957, Serial No. 44,824

Term of patent 7 years

(Cl. D26—14)

FIG. 1.

FIG. 2.

FIG. 3.

The back and the left side of the recorder are substantially plain.

The dotted line showing of tape magazines and a retaining drawer are for illustrative purposes only.

I claim:

The ornamental design for a magnetic recorder or similar article, as shown and described.
